F. M. GODDARD

SELECTIVELY OPERATED CIRCUIT CONTROLLING DEVICE

Filed July 12, 1919

Fig. 1.

Inventor:
Frederick M. Goddard.

by *J. E. Roberts* Atty.

UNITED STATES PATENT OFFICE.

FREDERICK M. GODDARD, OF BROOKLYN, NEW YORK, ASSIGNOR TO WESTERN ELECTRIC COMPANY, INCORPORATED, OF NEW YORK, N. Y., A CORPORATION OF NEW YORK.

SELECTIVELY-OPERATED CIRCUIT-CONTROLLING DEVICE.

Application filed July 12, 1919. Serial No. 310,507.

To all whom it may concern:

Be it known that I, FREDERICK M. GODDARD, a citizen of the United States, residing at Brooklyn, in the county of Kings, State of New York, have invented certain new and useful Improvements in Selectively-Operated Circuit-Controlling Devices, of which the following is a full, clear, concise, and exact description.

10 This invention relates to selectively operated circuit controlling devices and particularly to circuit controlling devices of the step-by-step type.

In electrical switching and signaling systems it is often desirable to selectively control from one station a plurality of circuits located at each of a plurality of way-stations. Especially in systems for the location of sources of mechanical vibrations in which 15 it is desired to selectively observe from one point the response thereto of a plurality of vibration detectors, it is advantageous to arrange such detectors in fixedly positioned groups within an area to be patrolled, the detectors being selected from the observing 20 point. In one system of this nature which has given satisfactory service in the detection of marine or submarine vessels within an area switching means provided for each 25 of several groups of detectors may be selectively advanced to a predetermined mechanically retained position and thereafter 30 may be selectively advanced to other electrically retained positions for controlling 35 electrically operated switching means to associate the detectors of the selected group with suitable transmission lines leading to the receiving means at the observer's station. Since such apparatus is usually submerged, 40 and is therefore not readily accessible, it is desirable to simplify the apparatus as much as may be possible in order to reduce to a minimum the necessity of inspection and adjustment, and due to the comparatively great 45 distances of the way-stations from the observing station, it is also desirable to employ switching means requiring a minimum of operating current.

It is an object of the invention to provide 50 a new and improved selectively operated cir-

cuit controlling device which is simple, compact and inexpensive.

To attain this object in accordance with a feature of the invention, a selectively operated step-by-step device is equipped with a 55 unitary switching mechanism adapted to selectively assume a plurality of operated positions in response to the advancement of the step-by-step device beyond a predetermined position and to control a plurality of 60 circuits in each of such positions. More specifically, a moving element of the step-by-step device is provided with means engaging an arm of a switching mechanism upon the attainment of a predetermined position by the 65 element to cause a plurality of contact arms to travel over and to selectively connect with a bank of contacts.

Another feature of the invention resides in the use of resilient conductors for the 70 electrical connection of the contact arms of a switching mechanism, which conductors also serve to restore the mechanism to its normal position. More specifically, coiled metallic springs are introduced in and form 75 parts of the conductors leading to the contact arms, such springs being stretched as the contact arms of the mechanism are advanced and the retraction of such springs, upon the release of the mechanism, restores 80 the contact arms to normal.

Other features of the invention not specifically mentioned above will more clearly appear from the following specification and the accompanying drawing, Fig. 1 of which 85 shows a plan view of a selectively operable device embodying the invention; Fig. 2 shows a side elevation of the same; Fig. 3 shows a perspective of the unitary switching mechanism removed from the associated selector, and with portions of the associated conductors omitted; Fig. 4 shows a plan view of the switching mechanism in an advanced position, and Fig. 5 is a detailed view 90 illustrating a position which the mechanism assumes in its operation.

In the drawings, the mechanism embodying the invention is shown as applied to, and controlled by, a selectively operated circuit controlling device disclosed in Patent 100

No. 1,343,256, patented June 15, 1920, by Joseph C. Field, similar reference characters being employed to designate such corresponding parts of the structure disclosed in the above-mentioned application as are necessary to a proper understanding of the invention. However, it is understood that any other suitable circuit controlling device of this general character may be used in connection with the invention.

A shaft 208 is supported by a suitable lower bearing 205 in a supporting plate member 200 cooperating with an upper adjustable bearing 206 in alignment therewith, threaded into a substantially U-shaped vertical side extension 204 of the plate member 200 and secured against displacement by a lock nut 207. A plate member 209 secured to the shaft 208 at an intermediate point thereof and rotatable therewith, is provided with an extension 210 and an actuating arm 203 diametrically opposite thereto. A substantially fan-shaped member 211 of insulating material is secured to the extension 210 by means of rivets or in some other suitable manner and carries radially extending contact arms 213 to 216, inclusive, secured thereto by means of rivets or in some other suitable manner. Each contact arm, constructed of lightweight metal and formed as shown to provide a maximum amount of resiliency with a minimum amount of friction, carries a suitable contact point at the extreme end thereof, which point rests upon the upper surface of a contact bank. The contact bank comprises a base 217 of insulating material secured to the plate member 200 by means of screw 218, in which base a plurality of contact pins 219 to 230, inclusive, are embedded so that their upper ends are substantially flush with the upper surface of the base and their lower ends project sufficiently below the lower surface of the base to provide suitable terminals for the attachment of wires or other conductors thereto. The contact pins are arranged in the arc of a circle described around the axis of the shaft 208 and corresponding to the arc described by the contact arms upon the rotation of the shaft. A plurality of terminals 231 for connection with the electrical circuits to be controlled are secured to the base 217 by rivets or in some other suitable manner and may be electrically connected to the lower ends of contact pins 221 to 228, (in accordance with circuit conditions) inclusive, by suitable conductors (not shown) or to rigid metallic conductors 233 to 236, inclusive, as desired. The rigid conductors 233 to 236, inclusive, are so formed as to terminate at points substantially over the contact arms 213 to 216 inclusive, respectively, and are electrically connected by means of solder, or in some other suitable manner, with

metallic coiled springs 237 to 240 inclusive, which extend to and are electrically connected with vertical terminals formed in the ends of the contact arms 213 to 216 inclusive, respectively. A member 241 suitably secured to the plate 200 by screw or otherwise, is provided with upturned portions 242 and 243 to limit the movement of the fan-shaped member 211 and the associated contact arms.

The assembled mechanism, as shown in Fig. 3, may be mounted upon a device such as disclosed in the above-mentioned patent by the provision of suitably threaded apertures in the plate 14 thereof to receive screws 201 and 244, the latter of which operates with screw 218 to properly position the base 217 on the plate member 200, a projecting pin 202 also being suitably mounted upon the upper surface of the wheel 20.

As shown in the drawings, 5, 5 designates the windings of an electromagnet controlling a centrally pivoted armature 6, which is polarized by means of a permanent magnet 7. Attached to the armature 6 is an elongated S-shaped arm 8 carrying at its free end a pin 9 and at a point intermediate its ends a pin 10, both pins being adapted to engage a pivoted lever 12 carrying at its upper end a stepping pawl 13. The coils 5, 5 and the cores on which they are wound are supported in a bracket 19 mounted on a suitable base (not shown), preferably of insulating material. Carried by the supporting bracket 19 is a frame composed of front and back members of plates 14 and 15 fastened together, between which there is a pin 16 upon which the lever 12 is pivoted in position to move the stepping pawl 13 into engagement with a ratchet wheel 17 mounted upon a shaft 18 journaled in the frame members 14 and 15. By means of a spring 45 the ratchet wheel 17 is normally retained in a position with a pin 56 therein in engagement with a stop member 57. The stepping pawl 13 is normally held against a stop pin 50 provided in the back frame member 15 by the action of a spring 51 attached at one end to the pawl 13 and at the other to the pivoted lever 12. An adjustable pin 52 mounted in a projection of the front frame member 14 limits the forward travel of the pawl 13. By means of a spring 43 secured at one end to the lower end of lever 12 and at the other to an arm 36 mounted on the back frame member 15 (see Figs. 1 and 5) the lever 12 is normally held in the position shown in Fig. 1 with the stepping pawl out of engagement with the ratchet wheel 17. The pins 9 and 10 engage the pivoted lever 12 upon opposite sides of the pivot axis or pin 16 and upon opposite faces in such a manner that with each movement

of the armature 6, in either direction, the stepping pawl 13 will cause a one-step movement of the ratchet wheel 17.

Mounted upon the shaft 18 carrying the ratchet wheel 17, and movable therewith, is a contact carrying member 20 carrying a pin 202. A holding spring 35 normally bears against an insulating knob or roller 37 carried by the lever 12. The spring 35 is so tensioned or bowed that in the neutral position of the armature the free end of said spring, which is provided with a curved projection 38, extends inside the circumference of a circle described by a holding member 55 in the movement of the contact carrying member 20. As the armature 6 moves, however, in response to current impulses through the windings 5, 5 of the electromagnet, the movements of the lever 12 will move the projection 38 at the free end of said spring 35 outwardly beyond the margin of the contact carrying member 20.

A holding pawl 40 is provided for preventing the dropping back of the ratchet wheel 17 during the time that the armature 6 is traveling from one extreme position to the other in response to a change in polarity of the energizing current. As shown, this pawl 40 is pivotally mounted upon the pin 16, and is adapted to be moved into engagement with the ratchet wheel 17 by means of a spring 41 secured at one end to the tail of the holding pawl 40 and at the other to an arm 39 mounted upon the back frame member 15 (see Figs. 1 and 5), and to be moved out of engagement therewith by a pin 42 in one end of the lever 12. The pin 42 normally keeps the holding pawl 40 out of engagement with the ratchet wheel 17 against the action of spring 41. It will be noted by reference to Figs. 1 and 5, (the right-hand end of armature 6 being attracted in Fig. 5) that at the time the lever 12 is moved by the arm 8 into position to bring the stepping pawl 13 into engagement with the ratchet wheel 17, the pin 42 will be separated from the end of the tail of pawl 40. As the arm 8 moves in the reverse direction and the lever 12 is moved about its pivot pin 16 by the spring 43, there will be a short interval of time before the projection 42 will engage the holding pawl 40. While the holding pawl 40 will actually be moved out of engagement with the ratchet wheel 17 before the reengagement therewith of the stepping pawl 13, the time intervening is so short that it will not be sufficient for the spring 45 to overcome the inertia of the ratchet wheel 17 and its associated parts.

The wheel 20 may thus be advanced by a suitable series and arrangement of successive impulses flowing through magnet windings 5-5, such impulses being of alternating polarity, until the grooved end of the holding member 55 is engaged by the projection

38 of member 35, in which position the element 20 is mechanically retained. Pin 202 simultaneously advances until it is in contact with the actuating arm 203 but does not change the position of such arm. However, an additional impulse of alternating polarity causes the pin 202 to advance and thereby move the arm 203 a predetermined distance until the contact arms 213 to 216 inclusive, are in engagement with contact pins 219, 222, 225 and 228 respectively. Another closely succeeding impulse will advance the arms until they disengage such contact pins and another closely succeeding impulse of alternating polarity will advance the arms until they are in engagement with pins 220, 223, 226 and 229 respectively, as shown in Fig. 4. Similarly, another closely succeeding impulse of opposite polarity will cause the arms to disengage the previously engaged contact pins and the next closely succeeding impulse of opposite polarity will advance them until they are in engagement with contact pins 221, 224, 227 and 230 respectively. The contact arms may be retained in any such advanced positions as long as the current is unchanged in polarity or is not removed from the coils 5-5 for a period longer than that intervening between the closely succeeding stepping impulses. Another closely succeeding impulse of alternating polarity will cause the arms to disengage the last-mentioned contact pins and will also, as described in the above-mentioned application, cause the disengagement of the projection 38 of the arm 35 from the member 55, thereby releasing the selector and restoring the step-by-step wheel 20 to normal.

As clearly shown in Fig. 4 when compared with Fig. 1, the springs 237 to 240 inclusive, are stretched as the associated arms 213 to 216 inclusive are advanced, thus storing energy therein so that each spring tends to restore its associated arm to normal. The forces thus applied by the springs at different points to the fan-shaped member 211 cooperate to cause the restoration of such member, and the contact arms carried thereby, to normal when the wheel 20 is released to disengage the pin 202 from the arm 203. The removal of current from the coils 5-5 for a period of sufficient length, unless the final or releasing impulse has been received, will restore the wheel 20 until the projection 38 reengages the hooked end of member 55. Consequently, the contact arms 213 to 216 inclusive, are thereupon restored to their normal positions, as shown in Fig. 1, irrespective of the particular advanced position occupied thereby.

It is evident that with the structure embodying the invention, a plurality of circuits at a selected station may be individually controlled from a distant station without

releasing the means used for selecting the station.

What is claimed is:

1. In a selectively operated circuit controlling device, a step-by-step element, an electromagnet, an armature responsive to a definite sequence of current impulses through the winding of the electromagnet, stepping means controlled by the armature for advancing the element step-by-step into a predetermined position, a plurality of stationary contacts, a movable contact selectively engaging the stationary contacts upon the advancement of the element beyond the predetermined position in response to additional impulses through the winding of the electromagnet, means controlled by and rendered effective by the deenergization of the electromagnet to return the element to its predetermined position, and means for returning the movable contact to its normal position upon the return of the element to its predetermined position.
2. In a selectively operated circuit controlling device, a step-by-step element, an electromagnet, an armature responsive to current impulses through the winding of the electromagnet, stepping means controlled by the armature for advancing the element step-by-step into a predetermined position, a plurality of stationary contacts, a rotatable shaft, a plurality of contact arms carried thereby, an actuating arm carried by the shaft, and means cooperating therewith and carried by the step-by-step element for rotating the shaft to cause the contact arms to selectively engage the contacts upon the advancement of the element beyond the predetermined position.
3. In a selectively operated circuit controlling device, a step-by-step element, an electromagnet, an armature responsive to current impulses through the winding of the electromagnet, stepping means controlled by the armature for advancing the element step-by-step into a predetermined position, a plurality of stationary contacts, a rotatable shaft, a plurality of contact arms carried thereby, an actuating arm also carried by the shaft, means cooperating therewith and carried by the step-by-step element for rotating the shaft to cause the contact arms to selectively engage the stationary contacts upon the advancement of the element beyond the predetermined position, means controlled and rendered effective by the deenergization of the electromagnet to return the element to its predetermined position, and means independent of the element for returning the contact arms to their normal position upon the deenergization of the electromagnet.

4. In a selectively operated switching device, an electromagnet, a bracket supporting the electromagnet, a frame removably

mounted on the bracket and containing a step-by-step element, stepping means therefor, an armature responsive to current impulses through the winding of the electromagnet and controlling the stepping means, a second frame removably mounted upon the first-mentioned frame and a bank of stationary contacts and a plurality of contact arms for engagement therewith under control of the step-by-step element mounted on said second frame.

5. In a selectively operated switching device in combination, a step-by-step element, an electromagnet, an armature therefor responsive to current impulses through the electromagnet stepping means controlled by the armature for advancing the element step-by-step into a predetermined position, a plurality of stationary contacts and a pivoted contact arm controlled by the step-by-step element in the movement thereof from the predetermined position for selectively engaging the stationary contacts.

6. In a selectively operated switching device in combination, a step-by-step element, an electromagnet, an armature therefor responsive to current impulses through the electromagnet, stepping means controlled by the armature for advancing the element step-by-step into a predetermined position, a plurality of stationary contacts, a pivoted contact arm, and means controlled by the step-by-step element in the movement thereof from the predetermined position for causing the pivoted arm to selectively engage the stationary contacts.

7. In a selectively operated switching device in combination, a step-by-step element, an electromagnet, an armature therefor responsive to current impulses through the electromagnet, stepping means controlled by the armature for advancing the element step-by-step into a predetermined position, a plurality of stationary contacts, and a contacting member normally stationary during the advancement of the element into its predetermined position and thereafter controlled by the movement of the element from the predetermined position for selectively engaging the stationary contacts.

8. In a selectively operated circuit controlling device, an element, an electromagnet, means responsive to current impulses through the winding of the electromagnet for advancing the element into a predetermined position, a plurality of stationary contacts, a movable contact selectively engaging the stationary contacts upon the advancement of the element beyond the predetermined position in response to additional impulses through the winding of the electromagnet, means for returning the element to its predetermined position, and independent means for returning the movable contact to its normal position.

9. In a selectively operated switching device in combination, an element, an electromagnet, means responsive to current impulses through the electromagnet for advancing the element to a predetermined position, a plurality of stationary contacts, and a contacting member normally stationary during the advancement of the element to its predetermined position thereafter controlled by the movement of the element from its said predetermined position for selectively engaging the stationary contacts. 10

In witness whereof, I hereunto subscribe my name this 10th day of July A. D., 1919.

FREDERICK M. GODDARD.
